(57) **CLAIM**

The ornamental design for housing for high-fidelity earbud, as shown and described.

DESCRIPTION

FIG. 1 is a front, right side, top perspective view of the housing for high-fidelity earbud showing my new design; FIG. 2 is a rear, left side bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof with the ear bud oriented rearwardly; FIG. 8 is a bottom plan view thereof;

FIG. 9 is a front, left side, bottom perspective view of the housing for high-fidelity earbud showing my new design; FIG. 10 is a rear, left side, bottom perspective view thereof; FIG. 11 is an inverted rear elevational view thereof; FIG. 12 is a rear, inverted, elevational view thereof; and FIG. 13 is a left side elevational view thereof; FIG. 14 is a right side elevational view thereof; FIG. 15 is a top plan view thereof; FIG. 16 is a bottom plan view thereof; and, FIG. 17 is a usage perspective view thereof. The broken lines depict environment that forms no part of the claimed design.
